United States Patent

Des. 239,684
Patented Apr. 27, 1976

239,684

TABLE OR THE LIKE

Stephen H. Robertson, 4108 Deep Hollow Drive, Apt. 277, and Randall L. Ward, 4102 Deep Hollow Drive, Apt. 284, both of Raleigh, N.C. 27612

Filed Feb. 18, 1975, Ser. No. 550,779

Term of patent 14 years

Int. Cl. D6—03

U.S. Cl. D6—177

FIG. 1

FIG. 2

FIG. 3

FIG. 1 is a perspective view of the table or the like showing our new design;

FIG. 2 is an end elevational view of the same, the opposite end thereof being substantially a mirror image of that shown; and

FIG. 3 is a side elevational view of such design, the opposite side being substantially a mirror image of that shown.

The bottom of the table or the like is substantially plain and unornamented.

We claim:

The ornamental design for a table or the like, as shown and described.
